UNITED STATES PATENT OFFICE.

FRANK P. D'ARCY, OF KALAMAZOO, MICHIGAN.

SPRING CONSTRUCTION.

Application filed December 9, 1925. Serial No. 74,308.

This invention relates to spring constructions and comprises all improvements over the prior art which are disclosed in this application.

5 One object is to produce a spring construction which is especially adapted for use on chairs and which can be rapidly and cheaply constructed and which will stand up well in practical use.

10 The above and other objects which will hereinafter appear, are attained by improvements embodying new and useful features as disclosed in this application. To enable others skilled in the art to fully comprehend the essential features of the improvements, drawings illustrating a preferred form have been annexed as a part of this disclosure.

Fig. 1 is a perspective view of portion 20 of a chair bottom with the spring construction applied thereto.

Fig. 2 is a bottom plan view of one of the spring slats forming part of the spring construction in Fig. 1.

25 Fig. 3 is a side view of one of the spring slats.

The spring construction comprises three spring slats 1 secured by nails 2 or otherwise to the bottom of a chair 3. A covering of 30 canvas or other material preferably is placed on top of the spring slats, and on the canvas is placed hair or any other suitable filling material, and then over this is placed a finish covering of any desired material such as 35 leather, velvet, etc.

Each spring slat 1 comprises two metal strips 4, 5, each strip being provided with 40 fastening holes 6 for nails or the like. Strip 4 has a struck up or pressed out projection 7 and a slot 8. Strip 5 has also a struck up or pressed out projection 9 extending through slot 8 of strip 4. Spring 10 has ends 11, 12 respectively engaging in the loops formed by pressed out projections 7, 9. 45 Thus the spring 10 holds pressed out projection 9 normally pressed against the end 13 of slot 8 and the portion 9 also holds strip 5 from undue lateral displacement relative to strip 4.

50 In operation, when pressure is placed upon strips 4, 5 (Fig. 1) they move endwise away from each other and bow downward thus bringing springs 10, located on the underside, into action and stretching

the springs, the projections 9 moving along 55 slots 8. When pressure is relieved, springs 10 contract and move projections 9 back against ends 13 of slots 8 thus causing strips 4, 5 to move endwise toward each other to raise the strips to normal position 60 again.

Without further elaboration, this disclosure will so fully reveal the gist of the improvements that others can, by applying current knowledge, readily vary these improvements without omitting certain features that, from the standpoint of the prior art, fairly constitute essential characteristics 65 of the generic and specific aspects of these improvements, and therefore such variations 70 are intended to be comprehended within the meaning and range of equivalency of the following claims:

I claim:

1. In a spring construction, spaced supports and a plurality of slats extending from one support to another, each slat comprising a pair of overlapping strips, one strip having a slot and the other strip having a projection engaging in said slot, and a spring 75 connecting said one strip with the projection on said other strip.

2. In a spring construction, spaced supports and a plurality of slats extending from one support to another, each slat comprising a pair of overlapping strips, one strip having a slot and the other strip having a pressed out projection engaging in said slot, and a spring connecting said one strip with the pressed out projection on said other 80 strip.

3. In a spring construction, spaced supports and a plurality of slats extending from one support to another, each slat comprising a pair of overlapping strips, one strip having a slot and a pressed out projection, and the other strip having a pressed out projection engaging in said slot, and a spring connecting the pressed out projection on one strip with the pressed out projection 85 on the other strip.

4. A spring slat comprising, a pair of overlapping strips, one strip having a slot and the other strip having a projection extending through said slot, and a spring connecting said one strip with said projection. 105

FRANK P. D'ARCY.
